HEATING FURNACE CONTROL

Application filed October 17, 1930. Serial No. 489,322.

This invention relates to improvements in the thermostatic control of furnaces used for heating houses, offices, shops and other buildings and the like. The invention is of special value and application in connection with the use of solid fuels such as coal and coke, and in the burning of gaseous fuel such as natural and manufactured gas, but it also has certain advantages in the burning of liquid fuels such as oil.

In conventional practice a thermostat actuated by the temperature in the enclosed space to be heated is arranged to initiate, or to accelerate or promote, combustion in the furnace when the temperature in this space falls below a predetermined minimum limit and to stop, or to retard or inhibit, combustion in the furnace when the temperature in this space rises above a predetermined maximum limit.

While the results so obtained are fairly satisfactory with respect to control of the temperature in that part of the enclosed space to be heated in which the thermostat is arranged, within the limits of the thermostats used, this practice disregards several elements, essential to efficient operation of the furnace and is subject to the limits of a single thermostat arranged in one part of the enclosed space to be heated.

The present invention provides an improved thermostat arrangement which has several important advantages. The invention includes an improved thermostat arrangement by which the several factors determining the temperature in the enclosed space to be heated and the efficiency of operation of the furnace are correlated to adjust each with respect to the others to secure satisfactory temperature regulation and at the same time to promote efficiency of operation. The invention also includes an improved thermostat arrangement avoiding many of the limits to which conventional thermostats conventionally arranged are subject.

The invention will be further described in connection with the accompanying drawing which illustrates, diagrammatically and conventionally, an embodiment of the invention. In the drawing Fig. 1 illustrates an embodiment of the invention including one particu-

larly advantageous thermostat arrangement and Fig. 2 illustrates a modified thermostat arrangement embodying, in certain respects, features described in my application filed September 6, 1930, Serial Number 480,045. It is intended and will be understood that the accompanying drawing is intended merely to illustrate the invention and that it is not to be interpreted in any limiting sense.

The accompanying drawing illustrates a heating furnace 1 which comprises the usual fire-box in which fuel is burned, heat transferring surfaces over which the hot products of combustion from the fire-box pass for the transfer of heat to the heating medium, air, water or steam for example, used in the heating system and a stack flue 2 communicating with a chimney 4 through which the hot gases from the fire-box which have passed over the heat transferring surfaces escape. The motor of a motor driven means for effecting combustion of fuel in the fire-box is shown at 3. The means shown comprise a fan arranged to provide forced draft through a grate on which coal or coke, for example, is burned. Instead of such a forced draft fan, an induced draft fan may be positioned in the stack flue. Or an oil burner, for example, may be arranged, generally with respect to the heating furnace, as shown in the drawing.

Instead of being arranged in the space to be heated, as in conventional practice, the thermostat 5, which is responsive to the temperature in the enclosed space to be heated is arranged in a thermostat chamber 6 appropriately insulated, thermally, and remotely situated with respect to the enclosed space to be heated, a room 7 in a building for example, which is connected to one or more pilot orifices, such as pilot orifice 8, in the enclosed space to be heated so that a flow of air is maintained from the enclosed space to be heated through the orifice 8 and thence through the chamber 6.

Several important advantages are thus secured, one of the more important of which is the avoidance of any limitation as to the size, which in turn is a limitation as to the accuracy and dependability, of the thermostat or

temperature responsive means used. Such pilot orifices, moreover, are unobtrusive and readily concealed, may be located with great freedom, tend themselves to promote the flow of air necessary to representative indication at the point of location of the mean temperature in the space to be heated, and do not afford an opportunity for casual tampering. In conjunction with electrically controlled systems, this thermostat arrangement makes it possible to localize wiring and also makes it possible to eliminate complications involved in the use of transformers, relays and the like necessary in low voltage control circuits, and, since usually a large proportion of the assembly can be completed at the factory, installation costs may be reduced.

In the embodiment illustrated the flow of air through the orifice 8 and connection 9 between this orifice and the chamber 6 is maintained by connections 10 and 11 between the chamber 6 and the chimney 4. A fan or blower or the like, as indicated at 12, may be provided to assist in maintaining this flow if the pressure differential provided by the chimney is irregular or insufficient. The connection 9 may be of any material reasonably air-tight and a poor conductor of heat, rubber or canvas or composite tubing for example. Such tubing may be easily "snaked" through floors, walls and partitions of conventional construction.

The thermostat chamber 6, moreover, may be made to integrate temperatures in a plurality of enclosed spaces to be heated by connection to similar pilot orifices arranged in each of them through connections corresponding to connection 9, such as 9' and 9" and so on, and the relative weights of the temperatures prevailing in each of such a plurality of spaces with respect to the operation of the thermostat 5 may be proportioned by valves or dampers, as indicated at 13, 13' and 13" for example, in the several connections.

The arrangement so far described, the provision of a thermostat chamber remotely situated with respect to an enclosed space or spaces to be heated and connected to one or more pilot orifices opening into the space or spaces with temperature responsive means adapted to control the heating furnace arranged in this chamber, is of general application in the burning of solid or liquid or gaseous fuels.

The control system illustrated in Fig. 1 comprises, in addition to the thermostat 5 responsive to the temperature in the enclosed space to be heated, a thermostat 14 responsive to the temperature of the gases escaping through the stack flue 2. The thermostat 14 is arranged in the thermostat chamber 15 which is connected to the exhaust connection 11 and, by means of connection 16, to a heat exchanger 17 arranged about the stack flue 2

so that the temperature of the gaseous medium flowing through the chamber 15 reflects the temperature of the gases escaping through the stack flue 2.

The thermostat 5 is adapted to close the power circuit through the motor 3 through contacts 18 as the temperature in the enclosed space to be heated falls and to open the circuit as that temperature rises and the thermostat 14 is adapted to lower the temperature at which the power circuit through the motor 3 is closed through contacts 18 as the temperature of the gases escaping through the stack flue 2 rises and to raise the temperature at which the power circuit through the motor 3 is closed through the contacts 18 as the temperature of the gases escaping through the stack flue 2 falls.

The temperature in the enclosed space to be heated and the temperature of the waste gases escaping through the stack flue, a significant measure of the efficiency of operation of the furnace, are thus correlated or counter-balanced so that proper weight is given to each in determining the operation of the combined control system. The two thermostats in the combined control system thus operate conjointly to control the furnace operation with respect to these several factors.

An auxiliary pair of contacts 19 may be provided to maintain the temperature of the gases escaping through the stack flue 2 above a predetermined minimum limit irrespective of the operation of the thermostat 5. A stop 20 may be provided to maintain the temperature of the gases escaping through the stack flue 2 below a predetermined maximum limit irrespective of the operation of the thermostat 5.

With the thermostat arrangement just described, the thermostatic means may be adjusted to provide for operation of the furnace under conditions approximating those of maximum efficiency when the demand for heat, as measured by the temperature in the enclosed space to be heated, is normal yet to permit operation of the furnace under conditions of increased capacity, though usually of decreased efficiency, during periods when the demand for heat is abnormal.

For example, this thermostat arrangement makes possible the operation of the heating furnace under conditions approximating those of maximum efficiency when the temperature of the enclosed space to be heated is, for example, within 2°-5° of the predetermined minimum limit yet provides for operation of the heating furnace at maximum capacity irrespective of efficiency should the temperature in the enclosed space to be heated for any reason fall say 20° below the predetermined minimum limit. For usual domestic heating purposes, for example, this thermostat arrangement provides

for an efficient furnace operation during that part of the day when the house is to be maintained at a predetermined temperature yet provides for furnace operation at maximum capacity when the house is to be brought to a predetermined temperature from some substantially lower temperature, a period during which capacity is more important than efficiency, as when an adjustment of the 5 temperature to which the control system responds is made say evening and morning, manually or by clock mechanism, for the maintenance of a lower temperature during one period of the day and of a higher temperature during another period of the day.

In the embodiment illustrated the pair of contacts 19 further provides for the maintenance of a minimum temperature of the stack gases, a matter of efficiency and in 20 the burning of solid fuels a matter of safety, irrespective of the temperature in the enclosed space to be heated and the stop 20 imposes a maximum limit, a matter of safety, upon the temperature of the stack gases.

25 The thermostats 5 and 14 in the embodiment illustrated are of the conventional bellows type. The exact form of the thermostats or temperature responsive means is not essential to the invention. Appropriate adjustments are provided, as indicated for example at 21, 22, 23, 24, 25 and 26.

It will be understood that the relative size, power and travel of the thermostats 5 and 14 and the relative increase or decrease of motion represented by the arrangement of linkages connecting the thermostats proper with the contacts, stops or other control means are to be proportioned with respect to the particular conditions for which the 35 thermostat is designed. It will also be understood that various other control elements, limiting controls for example, may be incorporated into the system just described without departing from the invention; limiting 40 controls operating against a predetermined maximum pressure limit in the case of steam heating systems for example.

The arrangement just previously described, the combined control system comprising correlated temperature responsive means operating conjointly to control the heating furnace with respect to the several factors involved, is of special application in the burning of solid fuels.

55 Some of the advantages of the invention may be secured if the arrangement of thermostats illustrated in Fig. 2 be substituted for that illustrated in Fig. 1. For the purpose of illustration that terminals *a* and *b* are indicated as the points of substitution. The same reference characters are used in Fig. 2 as in Fig. 1 to designate the same or corresponding parts.

With the arrangement illustrated in Fig. 60 2, the thermostat 5 is adapted to close the

power circuit through the motor 3 through contacts 27 when the temperature in the enclosed space to be heated falls below a predetermined minimum limit and to open this power circuit when this temperature rises 70 above a predetermined maximum limit and the thermostat 14 is adapted to close the power circuit through the motor 3 through contacts 28 when the temperature of the gases escaping through the stack flue 2 falls below a 75 predetermined minimum limit irrespective of the operation of the thermostat 5.

Having described my invention, I claim:

1. An improved heating control for a furnace connected to a chimney which tends to induce a draft through the furnace comprising a thermostat chamber remotely situated with respect to an enclosed space to be heated, a pilot orifice opening into said space and means including a connection between said orifice and said chamber for maintaining by means of pressure differential available from the chimney a flow of air from said space through said chamber, and temperature responsive means adapted to control said furnace arranged in said chamber.

2. An improved heating control for a furnace connected to a chimney which tends to induce a draft through the furnace comprising a thermostat chamber remotely situated with respect to a plurality of enclosed spaces to be heated, a pilot orifice in each of said spaces and means including connections between said orifices and said chamber for maintaining by means of pressure differential 100 available from the chimney a flow of air from said spaces through said chamber, and temperature responsive means adapted to control said furnace arranged in said chamber.

3. An improved heating control for a furnace connected to a chimney which tends to induce a draft through the furnace comprising a thermostat chamber remotely situated with respect to a plurality of enclosed spaces to be heated, a pilot orifice in each of said 105 spaces and means including connections between said orifices and said chamber for maintaining by means of pressure differential available from the chimney a flow of air from said spaces through said chamber, means for proportioning the flow through said several 110 orifices, and temperature responsive means adapted to control said furnace arranged in said chamber.

4. An improved heating control for a furnace connected to a chimney which tends to induce a draft through the furnace comprising a thermostat chamber remotely situated with respect to an enclosed space to be heated, a pilot orifice opening into said space and means including a connection between said orifice and said chamber and a connection between said chamber and the furnace stack for maintaining by means of pressure differential 115 120 125

available from the chimney a flow of air from said space through the chimney.

5. An improved heating furnace control comprising a pair of thermostat chambers remotely situated with respect to an enclosed space to be heated, a pilot orifice opening into said space and means including a connection between said orifice and one of said chambers for maintaining a flow of air from said space through the first chamber, means for maintaining a flow of a gaseous medium the temperature of which reflects the temperature of the gases escaping through the furnace stack through the other chamber, and thermostatic means adapted conjointly to control said furnace arranged in said chambers.

10 6. An improved heating furnace control comprising a pair of thermostat chambers remotely situated with respect to an enclosed space to be heated, a pilot orifice opening into said space and means including a connection between said orifice and one of said chambers for maintaining a flow of air from said space through this first chamber, means for maintaining a flow of a gaseous medium the temperature of which reflects the temperature of the gases escaping through the furnace stack through the other chamber, means for proportioning the flow through said chambers, and thermostatic means adapted conjointly to control said furnace arranged in said chambers.

15 7. An improved heating furnace control comprising thermostatic means responsive to the temperature prevailing in the enclosed space to be heated adapted to promote combustion of fuel in said furnace as that temperature falls and to inhibit such combustion as that temperature rises, and thermostatic means responsive to the temperature of the gases escaping through the furnace stack adapted to lower the temperature to which said first-mentioned thermostatic means responds to promote combustion of fuel in the furnace as the temperature of the stack gases rises and to raise the temperature to which said first-mentioned thermostatic means responds to promote combustion of fuel in the furnace as the temperature of the stack gases falls.

20 8. An improved heating furnace control comprising thermostatic means responsive to the temperature prevailing in the enclosed space to be heated adapted to promote combustion of fuel in said furnace as that temperature falls and to inhibit such combustion as that temperature rises, and thermostatic means responsive to the temperature of the gases escaping through the furnace stack adapted to raise the temperature to which said first-mentioned thermostatic means responds as the temperature of the stack gases rises and to lower the temperature to which said first-mentioned thermostatic means re-

25 falls and adapted to maintain the temperature of the stack gases above a predetermined minimum limit irrespective of the operation of the said first-mentioned thermostatic means.

30 9. An improved heating furnace control comprising thermostatic means responsive to the temperature prevailing in the enclosed space to be heated adapted to promote combustion of fuel in said furnace as that temperature falls and to inhibit such combustion as that temperature rises, and thermostatic means responsive to the temperature of the gases escaping through the furnace stack adapted to raise the temperature to which said first-mentioned thermostatic means responds as the temperature of the stack gases rises and to lower the temperature to which said first-mentioned thermostatic means responds as the temperature of the stack gases falls and adapted to maintain the temperature of the stack gases below a predetermined maximum limit irrespective of the operation of the said first-mentioned thermostatic means.

35 10. An improved heating furnace control comprising thermostatic means responsive to the temperature prevailing in the enclosed space to be heated adapted to promote combustion of fuel in said furnace as that temperature falls and to inhibit such combustion as that temperature rises, and thermostatic means responsive to the temperature of the gases escaping through the furnace stack adapted to raise the temperature to which said first-mentioned thermostatic means responds as the temperature of the stack gases rises and to lower the temperature to which said first-mentioned thermostatic means responds as the temperature of the stack gases falls and adapted to maintain the temperature of the stack gases above a predetermined minimum limit and below a predetermined maximum limit irrespective of the operation of the said first-mentioned thermostatic means.

40 11. An improved heating furnace control, comprising thermostatic means responsive to the temperature of the gases escaping through the furnace stack adapted to promote combustion of fuel in said furnace as the temperature in the stack falls and to inhibit such combustion as the temperature in the stack rises, and thermostatic means responsive to the temperature prevailing in an enclosed space to be heated adapted to raise the temperature to which the thermostatic means responsive to the temperature of the gases escaping through the stack responds to promote combustion of fuel in said furnace as the temperature in the enclosed space falls.

45 12. An improved heating furnace control, comprising a pair of thermostatic mechanisms, one responsive to the temperature prevailing in an enclosed space to be heated, and

the other to the temperature of the gases escaping through the furnace stack, each of said thermostatic mechanisms being adapted at different times to promote combustion of fuel in the furnace and to inhibit such combustion, said thermostatic means being so correlated that a change in the temperature which controls one thermostatic mechanism causes a change in the temperature at which 10 the other thermostatic mechanism is effective to change the rate of combustion of fuel in the furnace.

In testimony whereof I affix my signature.
